HARRY ELMER TIDMARSH, OF BANGOR, MAINE, ASSIGNOR TO UNION IRON WORKS,
OF BANGOR, MAINE, A CORPORATION OF MAINE.

WOOD-PULP GRINDER.

1,405,356.

Specification of Letters Patent. Patented Jan. 31, 1922.

Application filed February 28, 1921. Serial No. 448,490.

To all whom it may concern:

Be it known that I, HARRY E. TIDMARSH, residing at Bangor, in the county of Penobscot, State of Maine, have invented certain new and useful Improvements in Wood-Pulp Grinders; and I do hereby declare the following to be a full, clear, and exact description of the invention, such as will enable others skilled in the art to which it appertains to make and use the same.

This invention relates to wood-pulp grinders, and more particularly to the pockets used in multi-pocket grinders.

One of the common forms of mechanical wood-pulp grinders comprises a series of radial pockets disposed about the upper half of the grindstone periphery, into which the wood to be ground is placed and forced against the rapidly rotating stone. The ground wood is washed outwardly between the foot of the pocket and the stone or through slots in the base of the pocket walls and is carried away to the screens. It is a common defect of such grinders, however, that part of the wood ground in one pocket is carried around by the stone to succeeding pockets and reground. These successive grindings result in the production of so-called wood-flour in which the fibres have been ground so fine that they cannot be used in paper making. Such flour must therefore be separated from the rest of the pulp. It is clear then, that when the ground wood is carried from pocket to pocket there is a need less waste of both energy and material and an inferior non-uniform pulp results.

A device for avoiding this difficulty is shown and described in my U. S. Patent No. 1,231,671, July 3, 1917, and consists of a V-shaped deflector or plow held adjacent the stone and beyond each pocket except the last. The action of this plow is to intercept the pulp coming from its pocket along the periphery of the stone and deflect it outwardly to the edges and thus remove it from the grinder. It is the object of the present invention to devise other means for forcing the ground wood laterally from the peripheral face of the grindstone, such means being capable of independent use but preferably employed in conjunction with the plow or scraper described above.

This object is attained by diverging outwardly the slots in the base of the transverse walls of the pockets. The pulp emerging

through these slots is thus given an initial lateral thrust which tends to carry it over the edges of the stone, and when deflectors such as those described above are also employed the pulp is carried over to the edges of the stone with a minimum of effort.

In order that the invention may be more clearly understood, reference is had to the accompanying drawing disclosing a preferred embodiment thereof, and in which Fig. 1 is an elevation of a four pocket wood-pulp grinder; Fig. 2 is an elevation of one of the pockets of the grinder shown in Fig. 1; Fig. 3 is a vertical section through one of these pockets taken on line 3—3 of Fig. 1 and Fig. 4 is a plan of one of the pockets looking upwardly and showing one of the V-shaped deflecting scrapers positioned relative to the pocket.

The grinder thus illustrated comprises a rotary grindstone 1 mounted upon a shaft 2 supported in bearings 3 and rotating within a housing 4, upon which are adjustably mounted four radial pockets 5. Each of these pockets is provided with the usual hydraulic cylinder 6 in which the piston moves which actuates the pressure foot commonly employed in forcing the wood in the pocket against the rotating stone. The pockets 5 are adjustably mounted upon supporting members 7 through bolts 8, which are secured to the pockets through lugs 9. The pockets are fixed to the housing 4 in their adjusted position by means of bolts 10, which pass through the walls of the housing and slots 12 in depending aprons 13, which are integral with the pockets.

The grinder shown is also provided with deflecting scrapers 14, which are adjustably supported upon the rear sides of three of the pockets. It is obviously unnecessary to provide the last pocket with any scraping means. Each scraper is provided with two rods 15, which pass through outstanding lugs 16 on the rear face of each pocket and each scraper is adjustably secured to its pocket by means of suitable nuts. The foregoing arrangement is such that the scrapers are bodily adjustable with the pockets and likewise separately adjustable with reference to the pockets themselves.

Each pocket is provided with slots 17 in the base of its walls and it is through these slots that the ground wood escapes. The slots in the transverse walls 18 of the pockets

- are angularly disposed and are directed outwardly. Each transverse wall is provided with two series of slots which diverge outwardly as most clearly shown in Fig. 4. Diverging slots have been shown in both of the transverse walls of the pocket. It is clear, however, that the slots in only one wall, and that the rear wall, are in use at any given time. The slots in the forward wall serve no purpose. On the other hand, they are not detrimental and each pocket is cast with slots in both transverse walls, so that it may be employed on either a right or left hand grinder.
- 15 The operation of the grinder is as follows: Wood is fed into the several pockets and continuously forced against the grindstone which rotates in the direction indicated by the arrow. As the wood is ground some of it is washed outwardly through the slots 17 in the end walls of the pockets. This wood falls into the space between the housing and the stone and is eliminated. The rest of the pulp passes forwardly in the direction of movement of the stone through diverging slots 17. When it has passed from the pocket it impinges upon deflecting scraper 14 and is forced outwardly toward the edges of the grindstone and thus removed. The pulp in passing through the outwardly diverging slots is given an initial impetus which tends to force it over the edges of the stone. When the pulp having this lateral movement strikes against the scraper 14 it is easily deflected and forced over the side of the stone. Both scraper and pocket being adjusted to lie as close to the face of the stone as possible, it is practically impossible for any of the pulp to pass out of a pocket except through the slots, and also practically impossible for it to pass beneath a scraper and be carried into the adjoining pocket. In this way regrinding is eliminated and the efficiency of the machine increased accordingly.
- 45 Although the use of diverging slots has been shown and described and in connection with a V-shaped plow or scraper, it is clear that for a narrower stone it might be feasible to employ only one series of slots, all being parallel, but directed outwardly and used in conjunction with a plane, angularly disposed, deflector.
- I claim:
1. A pocket for wood-pulp grinders having slots in the base of one of its walls directed outwardly at an acute angle.
  2. A pocket for wood-pulp grinders having outwardly diverging slots in the base of one of its walls.
  - 60 3. A pocket for wood-pulp grinders having outwardly diverging slots in the base of its rear transverse wall.
  4. A wood-pulp grinder comprising a rotary grindstone, a pocket positioned radially thereof, an angularly disposed scraper be-

hind said pocket and outwardly directed slots in the base of the pocket wall adjacent the scraper.

5. A wood-pulp grinder comprising a rotary grindstone, a series of radially disposed pockets about said grindstone, angularly disposed scrapers behind certain of the pockets and outwardly directed slots in the base of the pocket walls adjacent the scrapers. 70

6. A wood-pulp grinder comprising a rotary grindstone, a series of radially disposed pockets about said grindstone, V-shaped deflecting scrapers behind certain of the pockets and outwardly diverging slots in the base of the pocket walls adjacent the scrapers. 80

7. A grinder for the production of wood pulp comprising a rotary grindstone, a plurality of pockets arranged around the stone 85 for receiving the wood to be ground and provided with means for feeding the wood against the stone, and scrapers arranged between the pockets and adjustable therewith with respect to the stone, said scrapers being arranged to remove the pulp produced and thereby prevent the same from passing to the next pocket and being reground, the base of each pocket wall adjacent a scraper being provided with outwardly directed 90 slots. 95

8. A grinder for the production of wood pulp comprising a rotary grindstone, a plurality of pockets arranged around the stone 100 for receiving the wood to be ground and provided with means for feeding the wood against the stone, and scrapers arranged between the pockets and adjustable with respect to both the pockets and the stone, said scrapers being arranged to remove the pulp produced and thereby prevent the same from passing to the next pocket and being reground, the base of each pocket wall adjacent a scraper being provided with outwardly directed slots. 105

9. A grinder for the production of wood pulp comprising a rotary grindstone, a plurality of pockets arranged around the stone 110 for receiving the wood to be ground and provided with means for feeding the wood against the stone, and scrapers arranged between the pockets for removing the pulp produced and thereby preventing the same from passing to the next pocket and being reground, each of said scrapers being mounted 115 upon one of the pockets and being adjustable with respect thereto, the base of each pocket wall adjacent a scraper being provided with outwardly diverging slots. 120

10. A grinder for the production of wood pulp comprising a rotary grindstone, a casting therefor provided with a plurality of pockets arranged around the stone for receiving the wood to be ground and having means for feeding the wood against the 125 130

stone, and scrapers arranged between the pockets and adjustable with respect to both the pockets and the stone, the adjusting means being outside of the casing, said 5 scrapers being arranged to remove the pulp produced and thereby prevent the same from passing to the next pocket and being reground, the base of each pocket wall adjacent a scraper being provided with outwardly diverging slots.

10 11. A grinder for the production of wood pulp comprising a rotary grindstone, a casing therefor provided with a plurality of pockets arranged around the stone for re-

ceiving the wood to be ground and having 15 means for feeding the wood against the stone, and scrapers arranged between the pockets for removing the pulp produced and thereby preventing the same from passing to the next pocket and being reground, each 20 of said scrapers being mounted upon one of the pockets and being adjustable with respect thereto, and adjusting means being located without the casing, the base of each pocket wall adjacent a scraper being provided with outwardly diverging slots.

In testimony whereof I affix my signature.

HARRY ELMER TIDMARSH.

Certificate of Correction.

It is hereby certified that Letters Patent No. 1,405,356, granted January 31, 1922, upon the application of Harry Elmer Tidmarsh, of Bangor, Maine, for an improvement in "Wood-Pulp Grinders," were erroneously issued to "Union Iron Works, of Bangor, Maine, a Corporation of Maine," as assignee of the entire interest in said invention, whereas said Letters Patent should have issued to the inventor, said *Tidmarsh and Union Iron Works, of Bangor, Maine*, said corporation being assignee of *one-half* interest only in said invention, as shown by the record of assignments in this office; and that the said Letters Patent should be read with this correction therein that the same may conform to the record of the case in the Patent Office.

Signed and sealed this 7th day of March, A. D., 1922.

[SEAL.]

WM. A. KINNAN,

Acting Commissioner of Patents.
